F. W. A. KRAUSE.
IMPLEMENT FOR SEALING RAILROAD CARS.

No. 18,400.

Patented Oct. 13, 1857.

UNITED STATES PATENT OFFICE.

F. W. A. KRAUSE, OF BALTIMORE, MARYLAND.

IMPLEMENT FOR SEALING RAILROAD-CARS, &c.

Specification of Letters Patent No. 18,400, dated October 13, 1857.

To all whom it may concern:

Be it known that I, FREDK. W. A. KRAUSE, of the city and county of Baltimore and State of Maryland, have invented certain 5 new and useful Improvements in Hand Implements for Sealing Railroad-Cars, Letter-Bags, &c.; and I do hereby declare that the following is a full, clear, and exact description of the same, reference being had to the 10 accompanying drawings, making a part of this specification.

By my improvement I furnish a portable hand implement for impressing with great facility, a suitable device upon metallic 15 blanks and compressing the same upon cord wire passed through said blanks in such a manner that the removal of the wire can not be effected without disfigurement of the seal, thus furnishing a ready mode of sealing the 20 doors of railroad cars, letter bags, etc.

The implement being provided with a cutter or knife for removing the wire, dispenses with the necessity of using a separate one, when the removal of the seal is required.

25 It consists of a pair of metallic handles which I designate as an upper and lower one; the upper one A, having its end so formed that it presents a flat face (b) and a section of a circle (a) eccentric to the center 30 of the pin (e) viz the circle (a) is struck from a point x on the periphery of the pin circle. The object of the flat surface (b) is to allow the upper die to rise in a manner hereinafter explained.

35 The lower handle B is provided with two uprights (c c) rising at right angles thereto, these uprights are connected by a cross piece (d) which serves as a guide and retainer of the upper die and the end of a spring.

40 (e) is a bolt passing through the uprights and also through the end of the handle A, thus connecting them. Through the cross piece (d) a cylindrical hole is formed for receiving the upper die (f) so fitted therein 45 as readily to be moved. Immediately below this opening is a recess or seat for the lower die (g) which is secured in the lower handle by a set screw. Both the upper and lower dies are provided with holes (o o) for the 50 passage of the wire cord and prevention against cutting.

(h) is a flat spring attached to the lower handle, its outer end enters a hole in the side of the cylinder forming the upper die,

the spring is guided by a slot or opening in 55 the cross piece (d).

The dies may have any suitable device engraved upon their sockets or cups.

K is a stud or rest secured on the upper handle, it is so formed at its lower end that 60 in part it forms a cutter or knife which is protected from being dulled by a small projection on said edge, which serves as a rest.

This implement is best and most economically constructed of cast iron, the parts 65 readily admit of being molded.

Suitable blanks or plombs having been made by casting a slot therein, and twisted wire cord being provided, the implement is opened by raising the handle A, thus giving 70 space for the rising of the cylinder and die by means of the flat spring (h) said spring also keeping the handle up.

The cord wire having been cut into suitable lengths is passed through the staples or 75 other fixture on the door of a car, then has its ends passed through the holes in the blank or plumb, then lay the metal plumb or blank in the socket of the lower die, observing that the cord wire lies in the holes 80 o o thereof, for preservation thereof when the upper die is brought down. The upper handle is then to be brought down slowly but firmly thus causing the eccentric on its end to press downward the upper die with sufficient force to impress the device of the seal 85 fully on the faces of the blank and at the same time compress the metal into closed contact with the twist of the wire cord, so that it cannot be removed or withdrawn 90 from the metal without disfigurement of the seal or impression; on the opening of the jaws the seal is released.

By the employment of the implement I have made, a more perfect impression is 95 made than can be done by the method now employed viz, a hammer and rest designed for effecting the same purpose.

To remove the seal or open a railroad car, the wire is brought under the cutter attached 100 to the upper handle, and by pressure applied by the hand of the operator thereon, the wire is cut and the seal detached.

It will be also noticed that this cutter serves as a stop or rest in the descent of the 105 upper die and cylinder.

Having described my improvement in sealing railroad cars, etc., what I claim as my

invention and desire to secure by Letters Patent, is—

The employment of the dies (*f* and *g*) when provided with holes (*o o*) therein for the protection of the wire cord, and when

said dies form a portion of the press for the purpose of impressing devices upon and compressing the metal of the seal upon wire

substantially in the manner and for the purpose set forth. 10

In testimony whereof I have signed my name before two subscribing witnesses.

F. W. A. KRAUSE.

Witnesses:

JOHN F. CLARK,

JOHN CARL MILLER.
